Patented Nov. 14. 1916.

Inventor

DAVID C. DANIEL

By *Watson E. Coleman*
Attorney

UNITED STATES PATENT OFFICE.

DAVID C. DANIEL, OF RAEFORD, NORTH CAROLINA.

CHURN.

1,204,849.

Specification of Letters Patent. Patented Nov. 14, 1916.

Application filed April 24, 1916. Serial No. 93,225.

To all whom it may concern:

Be it known that I, DAVID C. DANIEL, a citizen of the United States, residing at Raeford, in the county of Hoke and State of North Carolina, have invented certain new and useful Improvements in Churns, of which the following is a specification, reference being had to the accompanying drawings.

10 This invention relates to certain improvements in churning and has relation more particularly to a device of this general character wherein is comprised a working body, and it is an object of the invention to provide a churn with novel and improved means whereby the body may be readily and conveniently reciprocated in order to effect the churning operation.

It is also an object of the invention to provide a novel and improved churn wherein the body, when in applied position, is capable of yieldable movement independently of the operating means for reciprocating the same.

25 The invention consists in the details of construction and in the combination and arrangement of the several parts of my improved churn whereby certain important advantages are attained and the device is rendered simpler, less expensive and otherwise more convenient and advantageous for use, all as will be hereinafter more fully set forth.

The novel features of the invention will 35 hereinafter be definitely claimed.

In order that my invention may be the better understood, I will now proceed to describe the same with reference to the accompanying drawings, wherein—

40 Figure 1 is a view partly in elevation and partly in section illustrating a churn constructed in accordance with an embodiment of my invention, the retractile member for imparting independent upward movement to the upper cross head being shown in inoperative position; Fig. 2 is a sectional view taken substantially on the line 2—2 of Fig. 1 with the working body omitted; and Fig. 3 is a sectional view taken substantially on the line 3—3 of Fig. 1 with the working body omitted.

As disclosed in the accompanying drawings, 1 and 2 represent uprights of predetermined dimensions and having their lower extremities provided with the supporting

feet 3, and the upper portion of the upright 1 is preferably circular in cross section, as indicated at 4, for a purpose which will hereinafter be fully set forth.

The upper extremities of the uprights 1 and 2 are connected by the horizontal beam 5, while the lower end portions of the uprights 1 and 2 rotatably support the shaft 6 having one extremity provided with a balance wheel 7 and its opposite extremity with the pinion 8 in mesh with the driving gear 9 fixed to the stub shaft 10 rotatably supported by the upright 2 at a predetermined point intermediate the length of said upright. The stub shaft 10 as herein embodied, 70 is extended beyond the drive gear 9 and has coacting therewith the hand crank 11, whereby the requisite rotation may be imparted to the gear 9 for rotating the shaft 6. While I have herein disclosed the shaft 75 10 as adapted to be manually operated, it will be understood that it can be driven in any manner desired.

Arranged inwardly of the upright 2 but in close proximity thereto, is the vertically disposed post 12 preferably circular in cross section and having its lower extremity provided with an eye 14 through which the shaft 6 is loosely directed and whereby said shaft serves as a support or mounting for 85 the lower end portion of said post 12. The upper extremity of the post is operatively connected, as at 15, with the horizontal beam 5 hereinbefore referred to.

16 and 17 denote cross heads provided in their opposite extremities with the openings 18 through which the upright 1 and the post 12 are directed, said upright 1 and post 12 serving as guides for the heads 16 and 17 in their vertical movement. Positioned below the lower cross head 17 is an additional cross head 19 provided in its opposite extremities with the openings 20 through which the upright 1 and the post 12 are also directed for the purpose of guiding said head 19 in its movement. Interposed between the cross heads 17 and 19 are the expansible members 21 which permit a yielding movement of the cross head 17 independently of the cross head 19 and whereby the operation of my improved churn is materially facilitated.

The intermediate portion of the shaft 6 is preferably angular in cross section, as indicated at 22, in order to affix thereto the

eccentric disk 23, although it is to be understood that the disk 23 may be fixed to the shaft 6 in any desired manner.

The disk 23 is provided with the oppositely directed peripheral flanges 24 provided with the transversely alined recesses or notches 25, and underlying the flanges 24 are the inturned lips or extensions 26 of the yoke member 27 secured to and depending 10 from the cross head 19 at substantially its longitudinal center. It will be self-evident that the recesses or notches 25 hereinbefore referred to, readily permit the yoke 27 being operatively engaged with or removed 15 from the flanges 24.

Rotatably supported within the yoke 27 is the anti-friction roller 28 with which the periphery of the disk 23 is adapted to contact to impart upward movement to the head 20 19 and the head 17 through the medium of the interposed expansible members 21 herein disclosed as conventional coil springs. The coaction of the inturned lips 26 with the flanges 24 assure a positive downward 25 movement being imparted to the head 19 through the medium of the disk 23.

B denotes a churn body preferably cylindrical in form and produced of metal and having its upper end open, said open end 30 being closed by the cover C preferably of wood. I also find it of advantage to provide the churn body B with a glass covered slot 29 whereby visual access may be had within the body and also to provide the body with 35 the handle members H whereby the same may be conveniently manipulated. The churn body is adapted to be seated upon the cross head 17 with the upper cross head 16 resting upon the cover C thereof.

40 The upper surface of the cross head 16 is provided adjacent its opposite ends with the transversely disposed rock shaft 30 having its opposite extremities provided with the upstanding rock arms 31 with which are 45 pivotally engaged the extremities of the yokes 32 which straddle the cross head 16 and have their lower extremities pivotally engaged with the upstanding bars 33 carried by the lower cross head 17, whereby it will 50 be perceived that upon imparting upward movement to the rock arms 31, the body B will be effectively held or clamped between the heads 16 and 17.

The intermediate portion of each of the 55 rock shafts 30 is provided with the inwardly directed operating member 34 whereby the requisite movement may be imparted to the coacting shaft 30, and it is to be noted that the contact of said operating member 34 with the upper face of the cross head 16 60 serves to limit the movement of the shaft 30 in one direction or when adjusted to effect the clamping action upon the body B. It will be self-evident that reverse movement 65 of the shaft 30 will permit sufficient eleva-

tion of the head 16 to permit the removal of the body B from between the heads 16 and 17 and as herein disclosed, the upward movement of the head 17 is accomplished in an automatic manner through the medium 70 of the retractile member 35 herein disclosed as a coil spring interposed between and operatively engaged with the cross beam 5 and the upper head 16 at substantially their longitudinal centers.

75 It is preferred that the member 35 be permanently secured to the cross beam 5 but detachably engaged with the upper cross head 16 as it is my purpose to have the member 35 disengaged from the cross head 80 16 during the churning operation.

85 From the foregoing description, it is thought to be obvious that a churn constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof, and for this reason I do not wish to be understood as limiting myself to the precise arrangement and formation of the several parts herein 90 shown in carrying out my invention in practice.

95 I claim:

100 1. A churn comprising two vertical members, a shaft engaged with said vertical members, means for rotating the shaft, two cross heads slidably engaged with the vertical members, means carried by said vertical members for clamping a churn body therebetween, a third cross head slidably engaged with the vertical members and positioned intermediate the first named cross heads and the shaft, an expansible member interposed between the third cross head and the lower of the first named cross heads, and 105 coacting means carried by the shaft and the third cross head for reciprocating the cross heads upon rotation of the shaft.

110 2. A device of the character described comprising two uprights, a shaft rotatably supported by the uprights, a beam connecting the upper portion of the uprights, a post disposed in close proximity to one of the uprights and having its upper end secured to the beam, the lower end of the post being provided with an opening through which the shaft is loosely directed, means carried by the last named upright and coacting with the shaft for rotating the same, two cross heads slidably engaged with the post and the second upright and adapted to clamp a churn body therebetween, a second cross head slidably engaged with the second named upright and the post intermediate 115 the shaft and the lower of the first named 120 upright.

cross heads, a vibratory member interposed between the third cross head and the lower of the first two cross heads, and coacting means carried by the shaft and the third cross head for imparting reciprocatory movement to the cross head upon rotation of the shaft.

In testimony whereof I hereunto affix my signature in the presence of two witnesses.

DAVID C. DANIEL.
